LIGHTER

Ralph H. Segal and Theodore I. Segal,
Brooklyn, N. Y.

Application January 15, 1934, Serial No. 706,751

7 Claims. (Cl. 67—7)

This invention relates generally to lighters for igniting cigarettes and the like, and particularly to a lighter wherein the vapor evolved from a volatile fuel is caused or permitted to be absorbed by or contacted with or surround a catalytic substance or any other suitable substance whereby the said substance becomes incandescent, or the surrounding vapor ignited, or both.

One of the underlying principles upon which this invention rests is the heating of the catalytic element in a lighter for cigarettes and the like, without necessitating the puffing of the applied cigarette to do so, by forcing the fumes or fuel vapor into contact with the catalyst through mechanical means.

The structure involved contemplates the production of a complete cycle in which the fuel gas or vapor is forced into contact with the catalyst, causing heating thereof; the creation of a partial vacuum by which sufficient air is drawn in to be mixed with the vapor in readiness for its subsequent compression, the partial vacuum created in the vapor chamber allowing the fuel to evaporate more readily.

In one of its general aspects this invention comprises a casing having an expandible or plunger-like part wherein fuel vapor contained within the casing is made to contact with a catalyst by mechanical means, to heat the same, either by first causing compression of the fuel vapor by retraction of the expandible casing and then allowing it to expand for contact with the catalyst or by propulsion of the fuel vapor produced by retraction of the expandible casing, in which latter case the fuel vapor is directly propelled for contact with the catalyst, in both cases air being sucked from on top of or through the catalyst for mixture with the fuel vapor to present a fuel charge ready for action upon the catalyst at the next compression or retraction stroke of the casing.

A form of casing utilized in this invention comprises two irremovable telescopicable shell members having openings and coordinating communicating chambers to offer a passage for the vapors to the catalyst at predetermined times.

It is an object of this invention to provide novel means in compact form for lighting cigarettes and the like.

It is another object of this invention to provide in a lighter a valve by means of which the fuel vapor will be first compressed before being permitted to reach the catalytic element.

It is another object of this invention to construct the cigarette lighter whereby the catalytic

element is removed from contact with the fuel fumes or vapors when inoperative whereby the following advantages are derived; the prevention of continued chemical reaction in the device when inoperative, and therefore, consumption of the fuel immediately ceases; elimination of inert vapors, leaving active fuel gas always present in the fuel chamber; avoidance of wetting pill, such as, condensation of inert vapors upon the inner walls of the lighter.

It is another object of this invention to construct the lighter so as to cause a partial vacuum in the fuel chamber when the device is brought back again to the inoperative position, the creation of the vacuum reducing the pressure in the fuel chamber, the fuel, consequently, vaporizing more quickly and to a greater extent.

It is a further object of the invention to locate the parts of the lighter whereby air may be drawn in from the top of the catalyst into the fuel vapor chamber.

A still further object of the invention is to provide in a lighter contemplated by this invention, means to reduce the fuel vapor to a compact form, whereby the same is enabled to flow more rapidly in response to the puffing of the applied cigarette.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting preferred and modified forms have been annexed as a part of this disclosure, and in such drawings, like characters of reference denote corresponding parts throughout all the views, of which:

Fig. 1 is a top plan view shown in section of an embodiment of the invention in inoperative position.

Fig. 2 is a sectional view taken along line 2—2 of Figure 1.

Fig. 3 is a top view of the same.

Fig. 4 is a bottom plan view partly in section of the same in inoperative position.

Fig. 5 is a sectional view taken along line 5—5 of Figure 2, but shown in operative or compressed position.

Fig. 6 is a sectional view taken along line 6—6 of Figure 5.

Fig. 7 is a sectional view taken along line 7—7 of Figure 1.

Fig. 8 is a sectional view taken along line 8—8 of Figure 5.

5 Fig. 9 is a longitudinal sectional view of the device in a modified form, the same being shown in inoperative position.

Fig. 10 is a sectional view taken along line 10—10 of Figure 9.

10 Fig. 11 is a view similar to Figure 10, but showing a device in operative position.

Fig. 12 is a longitudinal sectional view of a still further modification of the device, the same being shown in inoperative position.

15 Fig. 13 is a longitudinal sectional view taken along line 13—13 of Figure 12, the device being shown in operative position.

Fig. 14 is a cross-sectional view showing a further modified form of the device.

20 Fig. 15 is a sectional view taken along line 15—15 of Figure 14.

Fig. 16 is a plan view of the device shown in Figure 14.

25 Fig. 17 is section view showing a still further modified form of the device.

In the drawings, the numeral 20 represents an inner receptacle in slidable or telescopic engagement with an outer receptacle 21. The receptacle 20 is shown as having a recess or pocket 22 to seat 30 one end of a spring 23, the other end of the spring bearing against the inside of end wall 24 of receptacle or shell 21. The spring 23 is shown as being helical, but it is understood that any suitable spring or other resilient means may be employed for the purpose intended, namely, to urge the inner shell 20 longitudinally outwardly with 35 relation to outer shell 21. The outer shell 21 is provided with a substantially central opening 26 adapted to register with chamber 27 of inner shell 20 when the latter is pressed inwardly. In substantially transverse alinement with opening or cavity 27 of the inner shell are the openings 28 and 29. Within inner shell 20 is a cage 30 adapted to receive a wick or other fuel absorbing 40 material 31, the latter encompassing the annular wall of chamber 27. Cage 30 is separated from the inner wall of the inner shell 20, thus forming a vapor space 32 all around the absorbent material. An opening 33 in the exposed end of inner shell 20 is provided for pouring in the fuel to be 45 absorbed by the element 31, a threaded cap 34 normally closing this opening.

The inner end 35 of inner shell 20 may be made removable for insertion of the absorbable material 31 and the screen or cage 30.

50 The bottom of outer shell 21 is provided with a trough or channel 36, the top opening 26 of the outer shell being disposed immediately thereover. Within chamber 27 is conveniently located a catalyst pill 37, having a perforation 37'. If the catalyst is made sufficiently porous, the perforation may be dispensed with.

The device in its normal inoperative position is shown in Figures 1 to 4 and 7. To operate the device, outer and inner shells 20, 21 are pressed longitudinally together against the action of spring 23, by the operator, assuming the position as shown in Figures 5, 6 and 8. This brings the catalytic element 37 in alignment with opening 26. The fuel saturated element 31 being suspended in the inner shell by means of the screen or cage 30, fuel vapor will accumulate in the space between the inner walls of the inner shell 20 and saturated element 31. When the device is in this position, the openings 28 and 29 of inner

5 shell 20 are over trough 36, thereby opening communication between the vapor chamber 32 and the ignition chamber 27. By the compressing action in chamber 33, vapor will be forced through orifices 39 and 40 as well as orifice 41 and will flow around the saturated element 31 and through orifices 28 and 29 into trough 36. From trough 36 the vapor will be forced into the ignition chamber 27 into contact with catalytic pill 37, heating the same.

10 During the telescoping of the shells 20 and 21, the fuel vapor and air already mixed therewith (the air having been sucked in on the intake stroke through opening 37') is being forced into contact with the catalyst 37 commencing the 15 heating thereof, orifices 28, 29 communicating with trough 26, and being propelled into chamber 27.

20 The cigarette is ignited by applying the same to the catalyst through opening 26, and puffing 20 on the same. When pressure is released on shells 20 and 21, the latter are urged apart by action of spring 23 thus recovering their initial positions, the chamber 33 becoming enlarged. During part of this expansion stroke, air is 25 sucked in through orifice 37' and commingles with the vapor within the shell compartments, the remaining part of the expansion stroke reducing the compression within the shells, thus aiding vaporization of the fuel. The charge is now 30 again ready for propulsion through the catalyst 37 by telescoping action of the shells 20 and 21.

35 As shown in the drawings the catalytic agent may be in the form of a suitable pill 37, the substance known as platinum black or platinum 35 sponge being preferably employed.

40 It is to be observed that when the device is in inoperative position, the catalyst is completely removed from the path of the fuel vapor, thereby preventing continued chemical action in the device when not in use, the inert vapors being eliminated, leaving active fuel gas always present in the fuel chamber. Furthermore, since the catalyst is removed from the path of the vapor, condensation of the vapors which may form on the 45 inner walls of the lighter, cannot possibly come into contact with the catalyst.

45 In the modification illustrated in Figures 9, 10 and 11, the numeral 50 indicates the outer shell and 51 indicates the inner shell. The outer shell 50 has a recess 52 at its closed end 53. Contained within this recess is a hollow plunger 54 which 50 operates valve 55 when in completely compressed position as illustrated in Figure 11. The hollow plunger 54 is utilized for filling the inner container 51 with the liquid fuel. A screw 56 is used to close the opening. Within the inner container 51 is located a cage 57 within which is located the absorbable matter 58. The cage 57 surrounds a hollow member divided into two communicating compartments 63 and 65 by a wall 64'. In line with plunger 54 and normally seated in an opening in an end wall of chamber or compartment 63 is a ball valve 55, normally held into seated position by spring 55'. The catalytic element 66 is supported in ignition chamber 65. Two 60 openings 59 and 60 are located at the inner wall 61 of the inner container 51, to offer communicating passages for the vapor in space 60' to chamber 62.

65 In telescoping the shells 50 and 51, the fuel vapor in chamber 62 and space 60' surrounding the wick 58, will first be compressed, and near the end of the compression stroke, the plunger 54 strikes the valve 55 thereby unseating the 70 75

same and permitting the compressed vapor to expand and enter chamber 63 and through the opening 64 into ignition chamber 65 and from there to the catalytic pill 66, heating the same.

5 The outer container 50 has an opening 67 for the insertion of the end of the cigarette to be lighted. Valve 55 is kept in fully closed position by compression spring 55. Compression spring 69 is utilized to hold the container 51 10 in a position illustrated in Figs. 9 and 10. It is understood that other resilient means may be employed for the purposes intended in lieu of the two springs.

While the device is inoperative, no fuel vapor 15 can reach the ignition chamber 65, holding catalyst pill 66.

The action in this device differs from that previously described, in that, in the former, the fuel vapor is first compressed and then after 20 completion of the compression stroke, plunger 54 operates the valve 55 to permit expansion of the previously compressed vapor, while in the latter, the fuel vapor is propelled by the telescoping of the shells 20 and 21. In other words, 25 in the device disclosed in Figures 1 to 8, of the drawings, the vapor reaches the catalyst by propulsion, whereas, in the device disclosed in Figures 9 to 11, the fuel vapor is first compressed and then allowed to expand to reach the catalyst.

Figs. 12 and 13 illustrate a still further modification of the invention. In this case, the catalytic pill is substituted by a filament 75. The outer casing 76 has a cigarette applying opening 35 77. The inner casing 78 is provided with a suitable plugged hole 79 used for refilling purposes. Inner casing 78 also contains the absorbent material 80 held within cage 81. On the inside of the end wall 82 of the outer case 76 is a recess 40 83 into which fits the end of a plunger 84. The other end of plunger 84 is provided with a valve cap 85, which shuts off the vapors from the ignition chamber 86, while the device is in inoperative position.

45 In this type of lighter, when parts 76 and 78 are telescoped the fuel vapor and air contained in chamber 87 will be forced through opening 88, and the air and fuel vapor in the space surrounding the wick 80, together with this fuel charge will be forced through opening 89 and out through the orifice opened by valve disc 85 and into ignition chamber 86, and contacting with the catalytic element 75, heating the same.

The surrounding fuel charge containing a supply 55 of air will be ignited by heat of the catalyst. Cigarettes applied above opening 77 may be ignited by the flame produced.

Compression spring 90 will normally keep the inner and outer compartments 76 and 78 in 60 their outward relation. The fuel charge reaches the catalytic element by propulsion, produced by the telescoping of the elements 76 and 78, the same as hereinabove described with respect to the device disclosed in Figs. 1-8.

65 Figs. 14 and 15 illustrate a still further modification of the invention. The outer container or housing 102 may assume any desired shape, such as, for example, round, square, hexagon, elliptical, oblong, etc. Housing 102 houses the 70 absorbable material 105 held in cage 106. The cage is shown as U-shaped. Forming part of or secured to housing 102 is an inwardly extending hollow member 115 divided by the transverse partitions 116, 117 into three compartments or chambers, a compression chamber 101,

an ignition chamber 110, and an auxiliary chamber 118. The cage 106 and wick 105 surrounds member 115, a space 119 being provided for the vapor resulting from evaporation of the fuel absorbed by wick 105. The compression in this device is accomplished by means of a hollow plunger 100 adapted to travel in the chamber 101. Openings 103 and 104 are provided in opposite walls of chamber 101, forming communication between chamber 101 and housing 102, 10 and another opening in the wall of auxiliary chamber 118. A spring 120 urges plunger 100 outwardly. A valve rod 108 secured to the top of plunger 100, slidably extends through a perforation in partition 116. In line with rod 108 15 and normally seated in an opening in partition 117 is a ball valve 109, normally urged into seated position by a spring 121. The valve 109 is unseated by rod 108 when depressed.

Catalytic element 111 is supported within chamber 110. Plunger 100 is provided with an opening 122. Normally, that is when the device is inoperative and the plunger is in extended position, a solid wall of the plunger is presented between the catalytic 20 111 and opening 122. When the plunger is depressed, then opening 122 registers with opening 112 and the catalytic element is then exposed ready for the cigarette to be applied thereto.

When plunger 100 is depressed, the fuel charge 30 (consisting of mixed air and fuel vapor) within plunger 100, chamber 101, housing 102, and auxiliary chamber 118 will be compressed. The plunger, near the end of its stroke will cause rod 108 to unseat ball valve 109 and allow the compressed fuel charge to expand into ignition chamber 110 and into contact with the catalytic element 111. The cigarette is inserted through opening 112 in shell 102. In this modification, the fuel charge reaches the catalytic element by compression and expansion.

It is to be noticed that while the device is inoperative, no vapor can reach the ignition chamber 110 which houses the catalytic element 111.

In the form of the invention disclosed in Fig. 17, there is provided the telescopic shells 130 and 131, the outer housing or shell 130 being normally urged outwardly with respect to the inner shell 131 by the spring 132. Inner shell 131 is divided into a plurality of compartments or chambers by 50 means of partitions. Compartment 133 shown as being at the bottom of the casing is the fuel compartment, fuel being admitted therein through an opening threadedly engaging a cap 134. At one side of compartment 133 is a tube 135, extending from near the bottom to the top thereof and terminating in or being in alignment with a nozzle 136 which may be formed out of the top 137 of the compartment 133. To one side and in proximity to nozzle 136 is a nozzle 138 which may be 55 formed out of a side wall 139 of cylinder or compartment 140 within which operates piston 141. Piston 141 has a stem or rod 141' secured to outer shell 130.

Nozzles 136, 138 project within compartment or 65 chamber 142 which is the fuel charge chamber, the latter communicating with the inside of outer shell 130. Also communicating with the inside of outer shell 130 is compartment or chamber 143 which communicates with ignition chamber 144, 70 in the latter of which is mounted the catalytic element 145, the part of chamber 144 above the catalytic element 145 being open as shown at 146. In the communicating opening between chamber 143 and outer shell 130 is seated a ball valve 147, 75

normally held in seated position by an attached stem or rod 149 secured to outer shell 130. Outer shell 130 has the cigarette applying opening 159, which normally (when the device is inoperative) is 5 out of alignment with opening 146 above catalytic element 145, the latter being covered by a closed part of the outer shell 130.

To operate the device shown in Fig. 17, outer and inner shells 130, 131 are relatively retracted. 10 During this procedure piston 141 forces vapor out of chamber 148 through nozzle 138, the same creating a suction and drawing out fuel in a fine spray through nozzle 136 (similar to an atomizer). The vapor emitted from nozzle 138 and the fuel 15 spray emitted from nozzle 136 constitute the fuel charge.

Relative retraction of the shells operates ball valve 147, the same being rigidly connected to outer shell 130. The fuel charge by propulsion 20 is forced into ignition chamber 144 into contact action with catalytic element 145 and heating the same. Relative retraction of the shells brings opening 159 over catalytic element 145. The cigarette may now be applied to the catalyzer.

If desired a suitable resilient gasket 280 (see 25 Fig. 1) may be interposed between the outer and inner shells to prevent leakage of vapors therebetween.

It is believed from the above description that 30 those skilled in the art will have no difficulty in understanding the construction, the method of use and operation of the devices herein disclosed and a detailed discussion thereof is unnecessary. The invention is of simple and practical construction 35 and is adapted to accomplish among others all of the objects and advantages herein set forth.

Without further analysis, the foregoing will so 40 fully reveal the gist of this invention that others can by applying current knowledge readily adapt it for various applications without omitting certain features, that, from the standpoint of the prior art, fairly constitute essential characteristics of the generic or specific aspects of this invention, and therefore, such adaptations should 45 and are intended to be comprehended within the meaning and range of equivalency of the following claims:

1. A lighter comprising a pair of telescopicable 50 receptacles, outer and inner respectively, the inner receptacle having a chamber, a catalyzer fixed in said chamber, the outer receptacle having an opening to the atmosphere, said opening registering with said chamber only when the receptacles are telescoped, said inner receptacle adapted to hold vaporizable fuel, means of communication 55 between the inner and outer receptacles for the vapor to expand when the receptacles are urged apart, and means of communication between said inner receptacle and said chamber to impart the vapor to the catalyzer when the receptacles are telescoped.

2. A lighter comprising a pair of telescopicable 60 receptacles, outer and inner respectively, the inner receptacle having a chamber, a catalyzer fixed in said chamber, the outer receptacle having an opening to the atmosphere, said opening registering with said chamber only when the receptacles are telescoped, said inner receptacle adapted to hold vaporizable fuel, and means of communication 65 between said inner receptacle and said chamber to impart the vapor to the catalyzer when the receptacles are telescoped.

3. A lighter comprising a pair of telescopic 70 receptacles, outer and inner respectively, means 75 normally urging the receptacles apart longitudi-

nally, the inner receptacle having a chamber, a catalyzer mounted in said chamber, the outer receptacle having an opening to the atmosphere, said opening registering with said chamber only when the receptacles are telescoped, a screen within said inner receptacle, liquid fuel absorbent material within said screen, the screen being spaced from an inner wall of said inner receptacle, means of communication between the inner and outer receptacles for the fuel vapor to expand when the receptacles are urged apart, the bottom of said outer receptacle having a trough disposed below said opening, and means of communication between said inner receptacle and said chamber through said trough to impart the vapor to the catalyzer when the receptacles are telescoped. 5

4. A lighter comprising a pair of telescopic receptacles, outer and inner respectively, means normally urging the receptacles apart, the inner 10 receptacle having a chamber, a catalyzer fixed in said chamber, the outer receptacle having an opening to the atmosphere, said opening registering with said chamber only when the receptacles are telescoped, said inner receptacle adapted to 15 hold vaporizable fuel, means of communication between the inner and outer receptacles for the vapor to expand when the receptacles are urged apart, the bottom of said outer receptacle having a channel, and means of communication between 20 said inner receptacle and said chamber through said channel to impart the vapor to the catalyzer when the receptacles are telescoped. 25

5. A lighter comprising a pair of telescopic receptacles, outer and inner respectively, means normally urging the receptacles apart, the inner 30 receptacle having a chamber, a catalyzer fixed in said chamber, the outer receptacle having an opening to the atmosphere, said opening registering with said chamber only when the receptacles are telescoped, said inner receptacle adapted to 35 hold vaporizable fuel, means of communication between the inner and outer receptacles for the vapor to expand when the receptacles are urged apart, and means of communication between said 40 inner receptacles and said chamber to impart the vapor to the catalyzer when the receptacles are telescoped. 45

6. In a lighter, the combination of, an outer 50 receptacle having a channel and an air admitting opening in alignment therewith, an inner receptacle slidably disposed in said outer receptacle and having a closed end normally overhanging said outer receptacle, said inner receptacle having an ignition chamber, a catalyzer within said chamber and means normally holding said chamber and catalyzer out of alignment with said opening and channel, said inner receptacle having means containing vaporizable fuel, said receptacles defining means to compress vapors evolved from said fuel during inward displacement of said inner receptacle, said receptacles having means to permit expansion of compressed fuel upon the retraction of said inner receptacle 55 and including means of communication to permit expanded fuel to enter said channel, said chamber defining means of communication permitting said vaporized fuel to flow from said channel to and by said catalyzer when said opening is in registration with said ignition chamber. 60

7. In a lighter, the combination of, an outer receptacle having a transversely disposed channel and an air admitting opening in spatial alignment therewith, an inner receptacle slidably relative to said outer receptacle and having a closed end 65

70

75

normally overhanging said outer receptacle, said inner receptacle having an ignition chamber, a catalyst disposed in said chamber and spring means coacting with said receptacles for normally holding said chamber and catalyst out of alinement with said opening and channel, said inner receptacle being displaceable inwardly against the action of said spring means to dispose said chamber and catalyst in alinement 5 with said channel and opening, said inner receptacle having means containing vaporizable fuel, said receptacles having means to compress

vapors evolved from said fuel on inward displacement of said inner receptacle, said receptacles having means of communication permitting said vaporized fuel to expand upon the retraction of said inner receptacle and enter said channel, said chamber defining means of communication permitting said vaporized fuel to flow from said channel to and against said catalyst only when said opening is in registration with said ignition chamber.

RALPH H. SEGAL.
THEODORE I. SEGAL.
